DESIGN FOR A COMBINED LAMP PEDESTAL AND BASE

Henry A. Perlmutter, New York, N. Y., assignor to Artistic Lamp Manufacturing Company,
Inc., New York, N. Y., a corporation of New York

Application December 8, 1939, Serial No. 88,761

Term of patent 3½ years

To all whom it may concern:

Be it known that I, Henry A. Perlmutter, a citizen of the United States, residing in the city and county of New York and State of New York, have invented a new, original, and ornamental Design for a Combined Lamp Pedestal and Base, of which the following is a specification, reference being had to the accompanying drawing, forming part thereof.

The figure is a perspective view of a combined lamp pedestal and base showing my new design.

I claim:

The ornamental design for a combined lamp pedestal and base, as shown.

HENRY A. PERLMUTTER.
